UNITED STATES PATENT OFFICE.

JOHN GLEN, OF BROOKLYN, NEW YORK.

DESIGN FOR A PRINTED FABRIC.

SPECIFICATION forming part of Design No. 13,350, dated October 24, 1882.

Application filed September 26, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of groups of flowers and flowering vines, as will herein-after appear.

Referring to the illustration, A represents a group of flowers, and B a flowering vine. The flowers and the vine are repeated upon the

fabric to form the pattern, although the flowers 20 A without the flowering vine may be repeated for such purpose.

The fabric may be produced in any preferred variety or combination of colors for giving a desirable effect to the design. 25

What I claim, and desire to secure by Letters Patent, is—

1. The design for printed and other fabrics, consisting of the group of flowers A, substantially as set forth. 30

2. The design for printed and other fabrics, consisting of the group of flowers A and the flowering vine B, substantially as described and shown.

JOHN GLEN.
